(57) **CLAIM**

The ornamental design for an exhaust silencer, as shown and described.

DESCRIPTION

FIG. 1 is a front, right, top perspective view of an exhaust silencer showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines and the deemphasized areas inscribed by the broken lines are for the purpose of illustrating portions of the exhaust silencer and do not form any part of the claimed design.

1 Claim, 7 Drawing Sheets
